UNITED STATES PATENT OFFICE

MORRIS STETTNER, OF BROOKLYN, NEW YORK

DESIGN FOR A FIREPLACE OR ARTICLE OF SIMILAR NATURE

Application filed December 15, 1930. Serial No. 37,987. Term of patent 7 years.

To all whom it may concern:

Be it known that I, MORRIS STETTNER, a citizen of the United States, residing in Brooklyn, New York, in the county of Kings and State of New York, have invented a new, original, and ornamental Design for a Fireplace or Article of Similar Nature, of which the following is a specification, reference being had to the accompanying drawing, forming a part thereof.

Fig. 2 is a side elevational view thereof.

I claim:

The ornamental design for a fireplace, or article of similar nature, as shown.

In testimony whereof I affix my signature.

MORRIS STETTNER.
